United States Patent Office.

J. W. GARDNER, OF SHELBURNE FALLS, MASSACHUSETTS.

Design No. 3,202, dated September 22, 1868.

DESIGN FOR A TABLE-FORK.

The Schedule referred to in these Letters Patent and making part of the same.

TO ALL WHOM IT MAY CONCERN:

Be it known that I, J. W. GARDNER, of Shelburne Falls, in the county of Franklin, and State of Massachusetts, have invented or produced a new and original Design for the Shape or Configuration of the Tines of Steel Table-Forks; and I do hereby declare the following to be a full, clear, and exact description of the same, reference being had to the accompanying drawings, making a part of this specification, in which—

Figure 1 represents, in perspective view, one of the forks in question.

Figure 2 represents a section taken across the tines to show their shape and configuration.

The nature of my design consists in rounding the backs of the prongs or tines of the fork, and making their front or inner sides square or flat, and thus give to the tines a shape or configuration that beautifies the article, and gives it greater commercial value.

A represents a fork, of which B are its tines. These tines are rounded on their backs, $\alpha\alpha\alpha$, and are flat on their front or inner sides, c , as seen in the cross-section, fig. 2, which represents the tines as semicircular in cross-section, or a section of a segment of a circle, which cross-section of course varies with the taper of the tines, but still of a rounded form at the back, and square or flat on the front.

Having thus fully described my design, what I claim, is—

The shape or configuration of the tines of table-forks, viz, rounded on their backs, and flat on their front or inner sides, as herein described and represented.

J. W. GARDNER.
